(57) **CLAIM**

The ornamental design for a battery clamp, as shown and described.

DESCRIPTION

FIG. 1 is a top perspective view of a battery clamp;
FIG. 2 is a top plan view thereof of the battery clamp shown
in FIG. 1;

FIG. 3 is a right elevational view thereof;

FIG. 4 is a left elevational view thereof;

FIG. 5 is a front elevational view thereof; and,

FIG. 6 is a rear elevational view thereof.

The ornamental design which is claimed is shown in solid
lines in the drawings. The broken lines shown represent
portions of the battery clamp that form no part of the claimed
design. A bottom plan view is not shown because it is a
mirror image to the top plan view shown in FIG. 2.
